UNITED STATES PATENT OFFICE.

HENRY B. ROBISCHUNG, OF KALAMAZOO, MICHIGAN, ASSIGNOR TO THE CHICAGO RAILWAY EQUIPMENT COMPANY, OF CHICAGO, ILLINOIS.

BRAKE-BEAM.

SPECIFICATION forming part of Letters Patent No. 549,021, dated October 29, 1895.

Application filed March 26, 1894. Serial No. 505,164. (No model.)

To all whom it may concern:

Be it known that I, HENRY B. ROBISCHUNG, a citizen of the United States, residing at Kalamazoo, in the county of Kalamazoo, State 5 of Michigan, have invented certain new and useful Improvements in Brake-Beams; and I hereby declare the following to be a full, clear, and exact description of the same, reference being had to the accompanying drawings, wherein—

Figure 1 is a top plan view of one end of a trussed brake-beam, the brake-head and collar partly in section to show my improvements in method of securing the head to the beam. Fig. 2 is a central section on the line 15 xx , Fig. 3. Fig. 3 is an end view of the beam with head attached, the tension member or truss-rod of the beam broken away. Fig. 4 is a central section of the collar, brake-head, 20 and end cap or sleeve separated on the axial line of the compression member of the beam. Fig. 5 is an end view of the end cap or sleeve. Fig. 6 is an end view of the collar. Fig. 7 is a sectional view of the head and collar, showing 25 my improved construction applied directly to the end of an ordinary beam, and also a slight modification in the construction of the head with the bearing-flange therefor on the beam.

Like symbols refer to like parts wherever 30 they occur.

My invention relates to the construction of 35 brake-beams in general, and has for its main object to permit an automatic endwise or axial movement of the head on the beam to ease the shock on the head and shoe, due to lateral (or axial) vibration of the beam in curving and under other conditions arising in the use 40 of brake-beams and brake-heads, and also to relieve the flange of the wheel from shock and undue frictional wear; and it has for its secondary object to permit the rotary automatic adjustment of the brake-head to meet any changes in the relation of the brake- 45 head (or brake-shoe) to the wheel, whether the same be due to tilting of the truck, change of load, change of position of beam to the line of draft, difference in height of beam above the track, (or hanging of beam,) or from any 50 other of several causes well understood by those skilled in the art.

To this end the main feature of my invention consists in the combination, with a brake-beam, of an automatically - yielding brake-head capable of longitudinal or axial movement on the beam to ease the shock due to lateral or axial vibration of the beam. 55

A second feature of my invention consists in the combination, with a brake-beam having a journal end, of a yielding brake-head 60 capable of rotary and axial movement on the beam, whereby said head can accommodate itself automatically to change of relation of the brake-head (or brake-shoe) to the wheel, as well as to lateral or axial vibration of the 65 brake-beam.

There are other minor features of invention, all as will hereinafter more fully appear.

For purposes of illustration I have chosen to show the present invention in connection 70 with a trussed brake-beam and an end cap commonly used in connection with hollow beams; but I wish it to be understood that the beam need not necessarily be a trussed structure, nor need an end cap be used, as the particular construction hereinafter specified for the end cap may be formed on or made integral with the end of the brake-beam. 75

I will now proceed to describe my invention more fully, so that others skilled in the art to 80 which it appertains may apply the same.

In the drawings, A indicates the compression member (or beam proper); B, the tension member, and C the end cap or sleeve of a trussed brake-beam, the compression and tension members A B being united with each other and with the end cap C by inserting the end of the compression member A into the end cap C, passing the threaded end of the tension member B through the end cap C, and 85 adjusting and securing the parts by a nut c in the usual manner, so that the end cap to all intents and purposes may be considered as a permanent part of the beam proper. This end cap C is formed at its inner end with a 90 bearing-flange 1 for the brake-head D to limit the inward movement of said head, and in the case of a common beam (see Fig. 7) said flange may be a collar formed with or shrunk on the structure. In either case it may be 95 beveled, as at 1^a, Fig. 7, which will serve to 100 keep out dust and also prevent any lodgment

of dust or matter which might prevent the brake-head from resting directly on the bearing-flange 1.

The outer end of cap C is provided with a 5 cotter-hole and cotter 2, or equivalent means of securing to the end of the beam an end collar or annulus 3.

The brake-head D, which may be of any approved form, has a suitable opening 4, by 10 which it is applied to the end of the brake-beam, and its inner cross-section exceeds the cross-section of the beam, or other provision is made to house a longitudinally-acting spring or equivalent means for holding the 15 head D up against the bearing-flange 1 with such elastic or yielding pressure as will permit of its movement in the axial line of the beam under sudden shocks, such as the vibration of the beam on an irregular track or 20 in rounding curves.

When, as in the present instance, a rotary motion of the head is desired, the end of the beam or the end cap is of cylindrical cross-section to form a journal, and the opening 4 25 of the head is of similar cross-section, though of increased diameter to accommodate a spring of spiral form, and is also provided at its inner side with an inwardly-projecting flange 5, which forms a seat or bearing for the 30 spring 6.

6 indicates a spring or equivalent means for seating the head with a yielding pressure, which, if of spiral form, will encircle the journal end of the beam or cap C, bearing at one 35 end on the flange 5 of the brake-head D and at the other on a collar or annulus 3, which annulus is of less diameter than the opening 4 of the brake-head and is adapted to enter the outer end of the brake-head opening 4 and 40 confine the spring 6, said collar 3 being secured to the end of the beam or cap C by a cotter-pin 2 or in other suitable manner. This spring 6 will under any circumstances be of sufficient power to hold the brake-head to its 45 seat on flange 1 under ordinary conditions, and in case the end of the beam is of journal form said spring 6 will be of force sufficient to exert a pressure and friction on the inner flange 5 of the brake-head to prevent the tipping or rotation of the brake-head by gravity 50 or other accidental force.

The sleeve or end cap C (or end of the beam) and the brake-head D being constructed substantially as hereinbefore specified, the head 55 is placed on the cap or end of the beam. The spring 6 is then slipped over the end of the beam within the cavity 4 of the head and with its inner end resting on flange 5. The collar

3 is then placed on the end of the beam with its inner end resting on the outer end of spring 60 6 and compressing the same, and is finally secured to the end of the beam by the cotter 2 or in other suitable manner.

When the parts are thus constructed and combined, the head will be at liberty to yield 65 in the axis of the beam to accommodate any lateral vibration of the beam and ease both the shoe or head and the wheel-flange, and it will also be at liberty to rotate automatically to adjust itself to any change in the relation 70 of wheel and brake-head, retaining the last-named adjustment until the same shall be again altered by the altered relation of wheel and brake-head.

Having thus described my invention, what 75 I claim, and desire to secure by Letters Patent, is—

1. The combination with a brake-beam of an automatically yielding brake-head arranged to move laterally or in the axial line of the 80 beam, substantially as and for the purposes specified.

2. The combination with a brake-beam of a laterally movable, automatically yielding rotatable head, journaled on said beam, substantially as and for the purposes specified. 85

3. The combination with a brake-beam, of a spring supported axially movable brake-head, substantially as and for the purposes specified.

4. The combination with a brake-beam, of a laterally or axially movable brake-head, and a spiral spring housed within the brake-head, substantially as and for the purposes specified. 90

5. The combination with a brake-beam, of a lateral or axially movable and rotatable brake- 95 head journaled on the beam, and a spiral spring housed within the brake-head, substantially as and for the purposes specified.

6. The combination with a brake-beam having a journal end, of a brake-head journaled 100 thereon, and having an inwardly projecting flange, a spiral spring housed within the head and encircling the journal end of the beam, and an annulus or collar of less diameter than the opening of the brake-head which annulus 105 is arranged to bear on the outer end of the spiral spring and is secured to the end of the beam; substantially as and for the purposes specified.

In testimony whereof I affix my signature, 110 in presence of two witnesses, this 22d day of March, 1894.

HENRY B. ROBISCHUNG.
